UNITED STATES PATENT OFFICE.

MILTON E. SHAVER, OF BURNHAM, ILLINOIS, ASSIGNOR TO PRESSED STEEL CAR COMPANY, OF PITTSBURGH, PENNSYLVANIA, A CORPORATION OF NEW JERSEY.

HAND BRAKE MECHANISM.

1,174,768.

Specification of Letters Patent. Patented Mar. 7, 1916.

Application filed November 4, 1912. Serial No. 729,396.

To all whom it may concern:

Be it known that I, MILTON E. SHAVER, a citizen of the United States, residing at 336 Park avenue, Burnham, in the county of Cook and State of Illinois, have invented certain new and useful Improvements in Hand Brake Mechanism, of which the following is a full, clear, and exact description, such as will enable others skilled in the art to which it appertains to make and use the same, reference being had to the accompanying drawings, which illustrate the preferred form of the invention, though it is to be understood that the invention is not limited to the exact details of construction shown and described, as it is obvious that various modifications thereof will occur to those skilled in the art.

An object of the present invention is to provide a brake mast of that type for use in flat cars or in freight cars which have drop ends or end doors, which are necessary where lading of great length is to be carried or where lading of great weight is to be distributed over two cars.

Another object of the present invention is to provide a telescoping brake mast, the operating portion of which may be dropped into the chain winding portion, and that when so dropped, the top of the hand wheel will be flush with or below the top of the car floor and will not interfere with the lading when the car is used as above described.

A further object of the present invention is to provide a plurality of brake masts with means common to both of said brake masts through which the brake mechanism may be operated.

A further object of the present invention is to provide a brake mechanism which may be manually operable either from the end sill of a car or from the track level at the side of the car.

A still further object of the present invention is to provide a vertical brake mast and a horizontal brake mast and to operatively connect them by a chain with the brake mechanism in such a manner that one of said brake masts will serve as an anchor for the chain when the other of said brake masts is operated.

Referring now to the drawings in which like reference characters refer to like parts and in which:

Figure 1 is a plan view of the end portion of a car with the improved hand brake

mechanism applied thereto; Fig. 2 is an end elevation of the same, Fig. 3 is a sectional view on the line 3—3 of Fig. 1, and Fig. 4 is a sectional view on the line 4—4 of Fig. 1. 60 Fig. 5 is a detail view of the chain winding portion of the vertical brake mast; Fig. 6 is a plan view of the same; Fig. 7 is a sectional view on the line 7—7 of Fig. 6 showing the supporting member in operative position, while Fig. 8 is a similar view showing the supporting member in inoperative position. Figs. 9 and 10 are detail views of a portion of the vertical brake mast. Fig. 11 is a sectional view on the line 11—11 of 70 Fig. 9; Fig. 12 is a similar view on the line 12—12 of Fig. 9 and Fig. 13 is a similar view on the line 13—13 of Fig. 9. Figs. 14 and 15 are detail views of the bottom portion of the operating part of the vertical brake 75 mast. Fig. 16 is a detail view of a modified form of the chain winding portion of the vertical brake mast; Fig. 17 is a plan view of the same. Fig. 18 is a sectional view on the line 18—18 of Fig. 17 showing the supporting member in operative position while Fig. 19 is a like view showing the supporting member in inoperative position and Figs. 20, 21 and 22 are sectional views on the lines 20—20, 21—21 and 22—22 respectively of 80 85 Fig. 16.

Referring now in detail to the drawings:—1 represents the draft sills, 2 the end sill and 3 the side sills. These sills are shown of channel form in the drawings, but it will be understood that any other suitable construction may be used.

4 represents the upper or operating part of the brake mast and 5 the operated or chain winding part of the brake mast, while 90 95 6 is the vertical brake mast bearing member which is riveted or otherwise suitably secured to the end sill.

The part 4 of the brake mast is made similar to the ordinary brake mast and is provided at the bottom with an enlarged portion 7 of any suitable shape, having an opening therein for the reception of a member hereinafter fully described, and at the top is provided with the ordinary hand wheel 8. 100 105 The enlarged portion 7 is shown in the drawings as being square in cross section, but it will be understood that other sections may be used equally as well.

The part 5 is hollow throughout its length 110 and is provided at the top with a ratchet wheel 9 for engagement with the pawl 10

which may be pivotally mounted on the bearing member 6, and at the bottom is provided with a lug 11, to which the chain 12 is attached, and is also provided with a portion 13 on which the chain 12 is wound. The inner surface 14 of the part 5 is made to form an opening 15 of substantially the same shape as the enlarged portion 7 of the part 4 for the purpose of permitting the part 4 to telescope within the part 5. At the top of the part 5, the surface 14 forming the opening 15, is flared outwardly and thus provides a recess within which the lower portion of the brake wheel 8 seats when the vertical brake mast is in inoperative position.

Intermediate the ratchet wheel 9 and the chain winding portion 13, the part 5 is provided at one side with an opening 16 which is widest at its central portion. On the side of the part 5 opposite the opening 16, a projection 17 is provided which is hollowed out on the inside and is provided with an opening 18. These openings 16 and 18 are provided for the reception of a member 19, such member being adapted to support the operating part 7 of the member 4 in operative position.

One end of the member 19 is provided with an enlarged portion or head 20, such head, when the member 19 is being moved into position to support the part 7 in its operative position, will contact with the outer walls of the projection 17 on the part 5 and will prevent it from being moved a distance greater than that intended. The end 21 of the member 19 is provided with an offset 22 which engages with the portion 23 of the part 5, and prevents the member 19 from moving endwise when it is in position to support the part 4. This offset 22 is also adapted to engage with the edge 24 of the opening 18 when the member 19 is in a position of rest, and when in such engagement will prevent any tendency to move away from the part 5, due to the shocks which a car is subject to in general use. The end 21 of the member 19 is also provided with projections or trunnions 25 which, when the member 19 is in a position of rest, contact with the inner walls of the projection 17 on the part 5 on each side of the opening 18 and prevent the member 19 from being accidentally separated or lost from the part 5.

The bottom portion 7 of the part 4 is provided with an opening which is of a suitable size to permit the member 19 being passed therethrough, the top and bottom of such opening being adapted to engage with said member 19 when the part 4 is in operative position. It will readily be seen that when the member 19 has been passed through the opening in the part 7 and finally through the opening 16 in the part

5, that such parts 4 and 5 are locked together and are not liable to become accidentally separated by the shocks to which a car is subjected.

In the modified form of the vertical brake mast as shown in Figs. 16 to 22 inclusive, the opening 15 in the part 5 is contracted at 35 to form a shoulder or abutment 36 with which the enlarged portion 7 of the part 4 is adapted to engage, such engagement preventing the accidental separation of the parts 4 and 5 when the part 4 is in operative position. It will readily be seen that by providing the shoulder or abutment 36, the opening in the part 7 for the reception of the member 19, as described in the preferred form may be eliminated. Above the contracted portion 35 the opening 15 in the part 5 is again widened for the reception of the lower portion of the hand wheel 8 when the part 4 is in inoperative position.

Besides being provided with a vertical brake mast the car is provided with a horizontal brake mast 26 one end of which is journaled to the side sill 3, the other end 90 being journaled in a bracket 27 which may be secured to either the draft sill 1 and the end sill 2 or to both. This brake mast is provided at its outer end with the ordinary hand wheel 28 and is also provided with a ratchet wheel 29 for engagement with the pawl 30 which may be pivotally mounted on the side 3 or on the side of the car. The other end of the mast 26 is provided with a slot 31 in which one end of the chain is secured by a bolt 32 or any other suitable means.

The chain 12 has one of its ends secured to the horizontal brake mast 26, and is passed over the sheave 33 which is operatively mounted in the brake rod jaw 34, the other end of the chain being secured to the part 5 of the vertical brake mast. It will thus be seen that when the vertical brake mast is used to apply the brakes the horizontal brake mast 26 serves as an anchor for the chain 12, and when the horizontal brake mast is used the vertical brake mast serves as an anchor for the chain 12.

When it is not desired to use the vertical brake mast the member 19 may be moved from its supporting position, as shown in Fig. 7 and the parts 4 and 7 telescoped within the part 5. It will be readily seen that when the parts 4 and 7 are telescoped within the part 5, the top of the brake wheel is flush with the top surface of the car floor, and when in such position is not liable to become accidentally damaged when the car is loaded with long material.

I am aware that minor changes in the construction, arrangement and combination of the several parts of the invention can be made and substituted for these herein shown and described, without in any way

departing from the nature and principle of the invention.

Having thus described my invention what I claim as new and desire to secure by Letters Patent is:—

1. In a car, the combination with a brake mechanism, of a plurality of brake masts arranged at one end of the car, a hand operating member on each of said masts, and a common flexible means secured to said brake masts through which said brake mechanism is operated.
2. In a car, the combination with a brake mechanism, of a vertical brake mast, a horizontal brake mast, both of said masts being mounted in one end portion of the car, a hand operating member on each of said shafts, and a common flexible means secured to both of said brake masts through which said brake mechanism is operated.
3. In a car, the combination with a brake mechanism, of a brake rod, a plurality of brake masts at one end of the car, and a common flexible means secured to both of said brake masts through which said brake rod is operated.
4. In a car, the combination with a brake mechanism, of a plurality of brake masts at one end of the car, and a common flexible means secured to both of said brake masts through which said brake mechanism is operated.
5. In a car, the combination with a brake mechanism, of a vertical brake mast adapted to be operated from the top of the car, a horizontal brake mast adapted to be operated from the side of the car, and common flexible means secured to both of said brake masts through which said brake mechanism is operated.
6. In a car, the combination with a brake mechanism, of a brake rod, a plurality of brake masts at one end of the car, hand operating means on each of said masts, and a common flexible means secured to said brake masts through which said brake rod is operated.
7. In a brake mast an operating part, an operated part and means slidably mounted within and extending through said operated part for supporting said operating part in operative position.
8. In a brake mast, an operating part, an operated part, a support loosely mounted within and extending across said operated part for supporting said operating part and means on said support adapted to engage with said operated part and prevent said support from moving out of supporting position.
9. A brake mast comprising a plurality of parts operatively connected together and means slidably mounted within and extending across one of said parts for supporting the other of said parts.
10. In a car, the combination with a brake mechanism, of a brake rod, a sheave mounted in said rod, a plurality of brake masts at one end of the car, hand wheels on each of said masts, and means passing over said sheave and attached to both of said masts. 70
11. In a car, the combination with a brake mechanism of a vertical brake mast, a horizontal brake mast, both of said masts being mounted at one end of the car, hand operating members on each of said masts, and a common flexible means secured to both of said brake masts for operatively connecting said brake masts with said brake mechanism. 75
12. In a brake mast comprising an operated part and an operating part, said operated part having formed therein an opening for the telescopic reception of said operating part, and means pivotally and irremovably mounted within said operated part to support said operating part. 80
13. The combination in a brake mechanism of a vertical telescopic brake mast, a horizontal brake mast, a hand operating member on each of said masts and means for operatively connecting said brake masts with said brake mechanism, one of said brake masts serving as an anchor for said means when the other of said brake masts is operated. 90 95
14. The combination with a brake mechanism, of a vertical brake mast, a horizontal brake mast, a hand operating member on each of said masts, and means for operatively connecting said brake masts with said brake mechanism, one of said brake masts serving as an anchor for said means when the other of said masts is operated. 100
15. The combination in a brake mechanism, of a plurality of brake masts, and common means anchored to said brake masts and operatively connected with said brake mechanism. 105
16. The combination in a brake mechanism, of a vertical brake mast, a horizontal brake mast, a brake rod, a sheave mounted in said brake rod and a chain passing over said sheave and anchored to both of said brake masts. 110
17. The combination in a brake mechanism, of a vertical brake mast, a horizontal brake mast and means for operatively connecting said brake masts with said brake mechanism, said vertical brake mast serving as an anchor for said means when the horizontal brake mast is operated. 115 120
18. The combination in a brake mechanism, of a vertical brake mast, a horizontal brake mast and means for operatively connecting said brake masts and brake mechanism, said horizontal brake mast serving as an anchor for said means when said vertical brake mast is operated. 125
19. In a brake mast, an operated part, an operating part, and means for locking said 130

parts together, said means being slidably and irremovably mounted in and extended across one of said parts.

20. A brake mast comprising a plurality of vertically disposed parts and means pivotally mounted within one of said parts adapted to lock said parts together.

21. In a brake mast, an operated part, an operating part operatively connected to said operated part and pivotal means passing through said parts adapted to support and lock said operating part in operative position.

22. In a brake mast, an operated part, an operating part having an opening therein, and supporting means pivotally mounted in said operated part adapted to be passed through said opening and lock said parts together.

23. A brake mast comprising a plurality of vertically disposed parts and means slidably and pivotally mounted in one of said parts adapted to lock said parts together.

24. In a brake mast, an operating part having an opening formed therein, an operated part having a plurality of openings formed therein, and means passed through said openings adapted to support and lock said parts together, said means being slidably and irremovably mounted in said operated part.

25. The combination with a telescopic brake mast, of a member mounted in one part of said brake mast adapted to support the other part of said brake mast, said member comprising a flat plate having an enlarged portion at one end and trunnions at the other end.

26. In a telescopic brake mast, an operating part, an operated part of cylindrical form, a shoulder formed within said operated part, means on said operating part adapted to engage said shoulder, and means slidably across said operated part adapted to support said operating part.

27. In a brake mast, an operated part, an operating part operatively connected with said operated part, and means extending through said operated part adapted to support said operating part in operative position, said means comprising a flat plate having an enlarged portion at one end and trunnions at the other end.

28. In a brake mast, an operated part, an operating part slidably in said operated part, and means slidably mounted in said operated part for supporting said operating part, said means comprising a member having an enlarged portion at one end and trunnions at the other end.

29. In a brake mast, an operated part, an operating part slidable in said operated part, a slidable member extending across said operated part for supporting said operating part in operative position, and means for automatically locking said member against longitudinal movement.

30. In a brake mast, an operated part, an operating part slidable in said operated part, a member slidable in said operated part adapted to support said operating part in operative position, said member being adapted to be automatically locked against longitudinal movement.

31. In a brake mast, an operated part, an operating part slidable in said operated part, a member slidable in said operated part adapted to support said operating part in operative position, said member being adapted to automatically lock itself against longitudinal movement.

32. In a brake mast, an operated part, an operating part slidable in said operated part, and a support for said operating part slidably and irremovably mounted in and extended through said operated part, said support comprising a flat plate having enlarged end portions.

33. In a brake mast, an operated part, an operating part slidable in said operated part, and a member irremovably mounted in said operated part adapted to support said operating part, said member being movable across said operated part into or out of supporting position with said operating part.

34. In a brake mast, an operated part, an operating part slidable in said operated part, a member slidably and pivotally mounted in said operated part adapted to support said operating part in its operative position, said member being irremovable from said operated part.

35. In a brake mast, an operating part and an operated part, said operated part having an opening formed therein for the telescopic reception of said operating part, and a member irremovably mounted in said operated part for supporting said operating part in operative position, said member being slidable across said opening into or out of supporting position with said operating part.

In testimony whereof I affix my signature in presence of two witnesses.
